UNITED STATES PATENT OFFICE

2,353,175

HINGE

Rollo Marple, Jackson, Mich., assignor to
 Hancock Manufacturing Company, Jackson,
 Mich., a corporation of Michigan

Application February 17, 1941, Serial No. 379,271

1 Claim. (Cl. 16—128.1)

The present invention relates to combined hinging and bracing structures, particularly adapted for, but not limited in their application to, automobile body structures. The Sullivan Patent No. 2,229,315, and the De Orlow Patent No. 2,091,673, disclose and claim hinging structures, and in certain of its aspects, the present invention is directed to improvements upon the Sullivan and De Orlow structures. More particularly, the present construction, as herein illustrated, employs hinge elements, the counterparts whereof are employed in the De Orlow construction and which function to give the same characteristic hinging movement as is afforded by the Sullivan construction. In the present arrangement, however, certain of the hinge elements, disposed at respectively opposite sides of the hinged body member, are interconnected in such a way as to enable these elements to materially brace the hinged member during its hinging movement.

With the foregoing general considerations in view, the principal objects of the present invention are to provide a combined hinging and bracing structure, which is simple in construction, economical of manufacture and assembly, and which provides improved operating characteristics; to provide such structures of the compound type, wherein a hinging movement involves a bodily movement of one of the hinged members relative to the other, and wherein, further, the hinge elements are interconnected in such a way as to brace the hinged member; to provide such structures embodying a pair of hinge assemblies spaced apart along the axis of hinging movement, and further embodying interconnections between said assemblies, which act to brace the hinged member; to provide such structures wherein each said assembly comprises a pair of link members, pivoted respectively to the hinged member and the cooperating structure, one link of each pair being interconnected whereby to brace the hinged member; and to in general improve the construction and operation of hinging systems.

With the above, as well as other and more detailed objects in view, which appear in the following description and in the appended claim, a preferred but illustrative embodiment of the invention is shown in the accompanying drawings, throughout the several views of which corresponding reference characters are used to designate corresponding parts and in which:

Figure 1 is a view in side elevation of an auto-

mobile hood hinging structure embodying the invention;

Fig. 2 is an enlarged detail view of certain of the hinge elements shown in Fig. 1;

5 Fig. 3 is a view in top plan of the structure shown in Fig. 1;

Fig. 4 is a detail view in vertical section, taken along the line 4—4 of Fig. 3; and

10 Fig. 5 is a view in vertical section, taken along the line 5—5 of Fig. 2.

It will be appreciated from a complete understanding of the present invention that the improvements thereof are susceptible of various uses. A preferred use, however, is in connection 15 with the hinging of automobile body parts, specifically the hood for an automobile engine compartment, and in an illustrative but not in a limiting sense, the present improvements are so disclosed herein. It will further be appreciated that 20 the invention may be embodied in structures of various different types, and the herein disclosed specific structure is, therefore, to be considered in an illustrative and not in a limiting sense.

Referring to the drawings, the present structure 25 comprises a pair of similar fixed brackets 10, located at respectively opposite sides of the dash 12, of an associated automobile body; a fixed bracket 16 secured to a part of the body structure spaced a substantial distance in advance 30 of the dash 12; a pair of movable brackets 18 positioned interiorly of, but at respectively opposite sides of the hood 20; and interconnections between the several brackets, comprising the rod-like links 22 and the links 24.

35 In accordance with conventional automotive practice, the cowl 26 is of crowned construction, and is integral with the forwardly extending side panels, such as 28, at respectively opposite sides of the engine compartment. The hood 20 is also 40 of crowned form and in accordance with conventional practice extends from the cowl to the radiator structure at the forward end of the engine compartment. In closed position, the rear marginal edge 20a of the hood seats upon an undercut ledge 30 formed at the forward marginal edge of the cowl, and the lateral side edges 20b of the hood seat against the upper edges of the side panels 28. In the closed position of the hood 20, accordingly, the entire hinging and bracing structure is concealed. A hinging movement 45 of the hood 20 causes the same to rotate about a moving, generally horizontal axis adjacent the cowl 26, and accompanying bodily movement of the hood is in a forward direction. The combined swinging and bodily movement of the hood 50

causes the rear marginal edge thereof to clear the ledge 30 without binding thereon.

The link 24 at each side of the body structure is pivoted by means of pins 32 and 34 to the brackets 10 and 18 at the corresponding side of the hood. Preferably and as illustrated, each link 24 is provided with an extension 36, which in the open position of the hood is disposed to abut a stop 38 struck from the corresponding bracket 10, so as to provide a limit to the opening movement of the hood 20.

The forward ends of the moving brackets 18 are interconnected by a stiffening member 40 and the respectively opposite ends of this stiffening member are provided with brackets 42, which form anchors for the pivot pins 44, associated with the rear ends of the respective links 22. The links 22 extend from the pins 44 in forwardly converging relation, and preferably and as illustrated, are rigidly secured together as by welding at a plurality of points, such as 46. The forward ends of the links 22 are pivoted by means of a pin 48 to a downwardly projecting portion 50, associated with the bracket 16, which may, in the broader aspects of the invention, be supported in various ways. In the present instance, advantage is taken of the usual stay rods 52, associated with the radiator structure 54, as a means for supporting the bracket 16. As will be understood, the stay bars 52 extend in crisscross relation from the radiator structure 54 to the dash 12, and the upper and lower halves 16a and 16b of bracket 16 are clamped to the bars 52 by means of the bolts 56.

In accordance with the disclosures of the above-identified Sullivan and De Orlow patents, spring mechanism may be and preferably is associated with the present structure, and in a generic sense, this spring mechanism may be arranged to continuously urge the hood towards the open position, to continuously urge it to the closed position, or to pass an over-center position during the course of the hinging movement. In the present instance, two springs 60 and 62 are utilized at each side of the hood structure. Each spring 60 is anchored at one end to the dash 12 and is anchored at the other end to the corresponding movable bracket 18. One end of each spring 62, in turn, is anchored to the dash 12 and the other end thereof is anchored to the corresponding link 24. For this purpose, each link 24 is provided with a slot 64 through which the corresponding end of the associated spring 62 is hooked. In the present instance, further, the springs 60 and 62 are arranged so as to continuously bias the hood 20 towards the open position, and it will be understood that suitable hood latch structure (not shown) may be employed to latch the hood 20 in the closed position. The springs 60 and 62 are preferably proportioned so as to substantially counterbalance the weight of the hood 20, thereby enabling the hood 20 to be lifted

upon release of the hood latch with a minimum of effort.

It will be appreciated that in certain instances the links 22 may require special formation so as to clear parts of the automobile engine. By way of illustration in the present instance, one of the links 22 is illustrated as being positioned above the usual air cleaner structure 66, and in order to enable such link 22 to clear the latter, the link in question is provided with an upwardly offset intermediate portion 22a.

In operation and as aforesaid, the hood 20, when in closed position, seats upon the cowl ledge 30, and upon the upper marginal edges of the side panels 28, under which conditions, the parts occupy the positions shown in full lines in the several figures, and in which positions the springs 60 and 62 are stressed to a degree which enables them to substantially counterbalance the weight of the hood 20. In order to lift the hood, the previously mentioned hood latch structure (not shown) may be released and an upward force applied to the front end of the hood. During the consequent lifting movement of the hood, the links 24 swing from the full line positions of the several figures to the dotted line positions thereof, and a similar swinging movement is imparted to the links 22. By virtue of the relative lengths and relative positionings of the pivot points for the links 22 and 24, the lifting movement of the hood causes the same to move bodily forwardly, which forward component of movement enables the rear marginal edge of the hood to clear the ledge 30 without binding thereon. It

will be appreciated that the links 24 are relatively short in length, and consequently these links can readily be arranged, together with their pivot pins, so as to give the necessary bracing effect to the rear end portions of the hood 20. A corresponding substantial bracing for the forward portions of the hood 20 is afforded by the rigidly interconnected links 22, which bracing effect not only prevents the front end of the hood from being moved back and forth laterally of the body, but also prevents the same from being warped.

What is claimed is:

In a hinging mechanism for controlling a hinging movement between relatively movable members, the combination of a pair of hinges, each hinge comprising a link having its respectively opposite ends pivotally connected to the respective members and having means associated therewith to cause a hinging movement to occur about an axis which moves through a predetermined path in a plane substantially normal to the axes of pivotal movement of said links relative to said members, one end of one of said links and the corresponding end of the other link having a common point of pivotal connection to the corresponding member.

ROLLO MARPLE.
